EQUALIZER BEAM FOR RAILWAY TRUCKS

Albert G. Dean, Narberth, Pa., assignor to The Budd Company, Philadelphia, Pa., a corporation of Pennsylvania

Application April 24, 1946, Serial No. 664,649

5 Claims. (Cl. 103—194)

1

The invention relates to railway trucks and more particularly to the equalizers associated therewith.

Railway trucks are well known to comprise a large proportion of the weight of the modern light weight railway car. A considerable portion of this truck weight is comprised by the equalizers resting on the tops of the journal boxes of the spaced truck axles, and this weight is unsprung weight. Any reduction in this unsprung weight is highly desirable. Equalizers as heretofore constructed of a solid bar of carbon steel of rectangular cross-section, were inordinately heavy.

It is an object of the invention to provide an equalizer of this class which is relatively light in weight while yet of adequate strength, and one which lends itself to fabrication inexpensively and without extensive machining operations.

This object is attained in large part by fabricating the equalizer in the main of an I-cross-section, the upwardly extending and vertically offset ends of which gradually merge with the I-cross-section of the main body to provide a cross-section in this critical heavily tension-stressed region near the journal seat having a heavy section at the bottom and a lighter section at the top, and designed to reduce the high tension stresses in this region to prevent danger of fatigue failure. The I-section of the main body preferably merges at the offset ends into an inverted T- or generally trapezoidal cross-section, and it will be obvious that a beam of this cross-section can be readily manufactured by drop forging operations, with a minimum of machining afterwards.

This cross-section of equalizer beam has a very high strength weight ratio and this can be further increased by choosing for the material of the beam high strength alloy steels suitably heat treated to high physical properties.

With the improved equalizer of the invention, it is readily feasible to save in the unsprung weight of a single 5½' x 10' truck in the neighborhood of 500 lbs. weight, or 250 lbs. per equalizer, over the trucks using the conventional rectangular cross-section carbon steel equalizer now in use, and this saving is in the important unsprung weight. Moreover, the weight saving may be accompanied by an increase in margin of safety, since the allowable stresses may be established at a lower percentage of the yield strength of the material as compared with the conventional carbon steel equalizers.

These and other and further objects and advantages will become apparent from the following detailed description when read in connection with the appended drawings forming a part of this specification.

In the drawings,

Fig. 1 is a side elevational view of a conven-

2

tional railway car truck, with the equalizer of the invention shown in heavy shaded lines and the remainder of the truck more or less diagrammatically in light unshaded lines.

Fig. 2 is an enlarged side elevational view of one end of the equalizer, showing in dot and dash lines a spring seat in relation thereto.

Fig. 3 is a plan view of the equalizer end; and

Figs. 4, 5 and 6 are sections taken, respectively, along the lines 4—4, 5—5 and 6—6 of Fig. 2.

The conventional truck to which the equalizer of the invention is shown applied may comprise the spaced wheel and axle assemblies 10, 10 carrying journal boxes 11, 11 at their opposite ends, which are vertically slidably received in the pedestals 12, 12 forming part of the truck frame 13. The truck frame 13 is carried by the equalizers through the spring nests 14, 14 which seat at their upper ends in spring seats 15, 15 on the frame and at their lower ends in spring seats 16, 16 carried by the equalizer 17. It will be understood that there are at least two such equalizers one supporting each side of the truck frame from the adjacent ends of the wheel and axle assemblies.

The equalizer 17 comprises a main body portion 18 of I-cross-section as clearly shown in Fig. 4 and extending horizontally at a low level, in the case shown, below the axles 19, 19 and carrying the spring seats 16, 16 adjacent its opposite ends. This main body portion 18 merges through curved portions 20, 20 into vertically extending portions 21, 21, which merge in turn through reversely curved portions 22, 22 into generally horizontally extending end portions 23, 23, which latter are adapted to seat on top of the journal boxes 11, 11 at the adjacent ends of the axles 19, 19.

In the critical region adjacent the journal box seat where the reversely curved portion 22 merges with the end portion 23 and in the end portion itself, according to the invention, the I-section of the main body of the beam is modified to more efficiently take the heavily concentrated tension stresses in this region. The cross-section in this critical region is substantially that shown in Fig. 5 which shows the bottom of the beam having a heavy tension chord portion 25 of the same width as the bottom chord of the main portion

50 of the beam but of much greater vertical depth (compare Figs. 5 and 4). In this region the top chord of the main portion 18 and the web are merged into a combined web and chord 26 narrower than the tension chord 25 and constituting the beam in this region of substantially inverted T- or generally trapezoidal cross-section. This merger of the I-section of the main body, as shown in Fig. 4, into the section of Fig. 5 proceeds gradually through the upwardly ex-

60 tending portion 21 and into the reversely curved

portion 22, as is clearly shown in Figs. 2 and 3, Fig. 3 showing in particular the top chord of the main I-section portion merging through inclined portions 27, 27 into the part 26.

This modification of the I-beam section at the point of maximum stress not only permits a lighter overall construction to take these high stresses but facilitates the formation of the entire equalizer as a drop forging, thus cheaping its manufacture.

At the extreme end where the equalizer rests on the adjacent journal box, it is preferably formed with a widened seat 28, see Figs. 2 and 6, extending laterally on both sides beyond the width of the tension chord portion 26. Such widened seat is desirable since it increases the wearing surface, both laterally and vertically, and this greatly increases the life of the equalizer. Also, it is possible with this arrangement to build up this widened seat by welding (in case of severe wear) without welding directly to the structural portion of the beam.

In Fig. 2, there is indicated in dot and dash lines, the approximate location of the neutral axis 29 of the equalizer beam. It will be noted that, the sectional conformation of the beam brings about the location of this axis close to the bottom margins of the beam in the critical end region. This greatly reduces the tension stresses in this critical region. While it at the same time results in somewhat higher compression stresses, these present no particular problem and do not normally tend to produce fatigue failure under usual operating conditions. This also increases the radius of curvature of this axis over that of the beam as a whole, which reduces the stress increase normally encountered in curved beams.

While the invention has been herein described in detail as applied to a specific embodiment, it will be understood that changes and modifications may be made by those skilled in the art without departing from the main features of the invention, and such changes and modifications are intended to be covered by the appended claims.

What I claim is:

1. An equalizer beam of the type having a main body portion extending horizontally and merging at its ends through first curved portions into upwardly extending inclined portions which in turn merge through second reversely curved portions into generally horizontally extending end portions designed to rest upon the journal boxes carried by the adjacent ends of spaced axles of a railway truck, characterized by the fact that the main body portion and the first curved portions are of I-cross-section, said I-cross-section merging gradually through at least portions of said upwardly extending portions and the second reversely curved portions into reversely curved portions and end portions throughout of generally trapezoidal cross-section materially heavier at the bottom than at the top, thereby increasing the radius of the curvature of the neutral axis of the beam in this heavily stressed reversely curved region substantially over the curvature of the beam as a whole whereby the beam is more uniformly stressed throughout this reversely curved end portion thereof.

2. An equalizer beam of the type having a main body portion extending horizontally and merging at its ends through first curved portions into upwardly extending inclined portions which in turn merge through second reversely curved portions into generally horizontally extending end portions designed to rest upon the journal

boxes carried by the adjacent ends of spaced axles of a railway truck, characterized by the fact that the main body portion and the first curved portions are of I-cross-section, said I-cross-section merging gradually through the upper portions of said upwardly extending portions and parts of said reversely curved portions into the remainder of said reversely curved portions and end portions throughout of generally inverted T-cross-section materially heavier at bottom than at top, thereby increasing the radius of the curvature of the neutral axis of the beam in this heavily stressed reversely curved region materially over the curvature of the beam as a whole in said region.

3. A forged equalizer beam having a main body portion extending horizontally and extended upwardly at its ends to merge through curved portions into horizontally extending extremities adapted to seat upon adjacent journal boxes of a railway truck, the main body being of I-cross-section merging gradually, in the critically stressed region through the curved portions, into the curved portions and the horizontally extending extremities throughout of a cross-section materially heavier at the bottom than at the top, thereby increasing the radius of the curvature of the neutral axis of the beam in this critically stressed region substantially over the curvature of the beam as a whole in this region.

4. A forged equalizer beam for railway trucks having a main body portion extending horizontally and extended upwardly at its ends to merge through curved portions into horizontally extending extremities adapted to seat upon adjacent journal boxes of a railway truck, the main body being of I-cross-section merging gradually into the curved portions and end extremities throughout of a cross-section having materially greater width and mass adjacent the bottom than adjacent the top, thereby substantially increasing the radius of the curvature of the neutral axis of the beam in the critically stressed region through the curved portions over that of the main body of the beam in this region.

5. A forged equalizer beam having a main body extending horizontally and extended upwardly at its ends to merge through curved portions into horizontally extending extremities adapted to seat upon adjacent journal boxes of a railway truck, the main body being of I-cross-section merging gradually through portions of the upwardly extending portions and the curved portions into curved portions and end extremities of a different cross-section having a lower portion throughout of materially greater cross-sectional area than the cross-sectional area of the bottom chord of the I-cross-section of the main body of the beam, thereby increasing the radius of the curvature of the neutral axis of the beam in this critically stressed curved region substantially over the curvature of the beam as a whole.
